ABSTRACT OF THE DISCLOSURE

A thin annular inside diameter cutting blade having its peripheral edge portion loosely received between a pair of clamping rings is firmly held in a flat condition while the rings are shifted in unison, edgewise of the blade, as needed to bring the rings into concentricity with the blade. The direction or directions the rings must be shifted and the extent thereof is determined by reference to an optically observed spacial relationship between the inner cutting edge of the blade and a circumferential surface on one of the rings. When concentricity is established the rings are drawn together to clamp the blade therebetween.

This invention pertains to cutting tools of the type comprising a thin annular blade with an inside diameter cutting edge, and the invention relates more particularly to a method and means for mounting such a blade in true concentric relation to a chuck by which the blade is rotatably carried and for applying tensioning force to the blade uniformly all around the same.

Annular blades of the type with which this invention is concerned, sometimes referred to as "inside diameter" blades, are made of very thin stock and have diamond bort around the inside edge of the blade. Such blades, because of their thinness, are now generally used for slicing crystals of germanium, silicon, quartz and the like in the manufacture of electronic components, because the narrow kerf produced by an inside diameter blade conserves valuable crystal material. However, the mounting of such a blade presents serious problems arising out of its lack of rigidity. It is of obvious importance that the blade be mounted truly concentrically in the chuck by which it is carried, in order to avoid radial chatter as the blade is rotated in cutting engagement with a workpiece. It is also important, in order to prevent flatwise displacement of an inside diameter blade during cutting, that it be mounted in tension, and that such tension be uniform all around the blade.

While the tensioning of the blade is achieved by applying radial force to the blade in a zone spacedly radially from its inner edge, the application of such force produces circumferential stresses near the inside diameter cutting edge and is therefore referred to hereinafter as circumferentially stressing or tensioning the blade.

Such expedients as have heretofore been employed for achieving concentricity and circumferential stressing of a thin annular blade with an inside diameter cutting edge have not been completely satisfactory. In one prior arrangement the blade was secured to a chuck by means of a clamping ring, and the opposing annular faces of the chuck and clamping rings were respectively provided with a rounded concentric groove and with a mating rounded projection. The projection on the one forced the flat contacting area of the periphery of the blade into the groove in the other as the ring was fastened to the chuck, thereby circumferentially stressing the blade. Once a blade had been clamped between the chuck and clamping ring of this arrangement, it was permanently deformed by

the cooperating projection and groove, and therefore if the blade was not established in concentricity to the chuck when the clamping ring was tightened, the blade had to be discarded unused. Unfortunately the arrangement just described made no provision for accurately positioning the blade in concentric relation to its chuck.

In another arrangement, the peripheral portion of the blade was clamped between a pair of rings having opposing flat faces, and the rings cooperated to provide a holder that could be concentrically secured to a chuck. A tension ring having a concentric axially inwardly projecting annular portion was screwed into one of the rings until it engaged the blade and displaced the central portion thereof a small distance axially inwardly. The axial offset of the central portion of the blade that was maintained by the tension ring effected the necessary circumferential tensioning of the blade, but did so at the expense of imposing unpredictable and undesired torsional stresses upon the blade due to friction between the blade and the tension ring as the latter was rotated in engagement with the blade, so that there could be no assurance that circumferential tension was uniform all around the blade.

With these and other objections to prior expedients in mind, it is a general object of the present invention to provide a method and means for establishing a thin annular blade having an inside diameter cutting edge in true concentric relation to a chuck by which the blade is rotatably carried, and for circumferentially tensioning the blade uniformly all around the same without imposing unwanted torsional or other stresses upon the blade; and to achieve these ends, moreover, in a facile and expeditious manner, with relatively simple and inexpensive apparatus, and without entailing any risk of damaging the blade before it is used.

Another and more specific object of this invention is to provide a simple fixture which is adapted to cooperate with a pair of clamping rings that provide a holder by which a blade of the character described can be mounted on a chuck, which fixture enables a blade to be established in true concentricity to the clamping rings, and hence to the chuck, without requiring the imposition of any stress or strain upon the blade and without any necessity for touching the cutting edge of the blade.

A further specific object of this invention is to provide a quick and easy method of centering an annular blade with respect to a pair of clamping rings that provide a holder by which the blade can be concentrically mounted on a rotatable chuck, in which method the blade is clampingly confined against edgewise motion while the clamping rings, locked into concentric relationship with one another with their opposing surfaces lightly flat-wise engaging the peripheral portions of the blade at opposite faces thereof, are shifted in unison as required to bring them into concentricity with the blade; and then, while the rings are maintained in concentric relation to the blade, they are drawn together and releasably locked in clamp ing relationship to the blade.

Still another specific object of this invention is to provide apparatus for radially tensioning an annular blade which is clamped between a pair of clamping rings that provide a holder by which the blade can be concentrically mounted on a chuck, said apparatus comprising a tension ring receivable in one of the clamping rings, and force applying means for imparting an axial purely translatory motion to the tension ring to force it into tensioning engagement with the blade, said force applying means preferably having elements in common with the above mentioned fixture for centering the blade in the clamping rings.

It is also a specific object of this invention to provide a method of establishing circumferential tension in

an annular blade clamped between a pair of clamping rings, in which method axial force is applied uniformly and simultaneously at all points around a tension ring that is received in one of the clamping rings, to advance the tension ring into the clamping ring with an axial purely translatory motion until the tension ring reaches a position at which it holds the central portion of the blade axially offset by a predetermined amount from the peripheral portion of the blade; and, while the tension ring is held in said position by the continued application of coaxial force thereto, it is releasably locked to one of the clamping rings.

With the above and other objects in view which will appear as the description proceeds, this invention resides in the novel method and apparatus substantially as hereinafter described and more particularly defined by the appended claims, it being understood that such changes in the precise embodiment of the herein disclosed invention may be made as come within the scope of the claims.

The accompanying drawings illustrate one complete example of the physical embodiment of the invention constructed and practiced according to the best mode so far devised for the practical application of the principles thereof, and in which:

FIGURE 1 is a fragmentary view, partly in side elevation and partly in vertical section, of a machine tool which incorporates a thin annular blade having an inside diameter cutting edge, the work supporting table and related portions of the machine tool being omitted;

FIGURE 2 is a front perspective view of the chuck of the machine tool shown in FIGURE 1 with an annular inside diameter cutting blade mounted in a holder concentrically carried by the chuck;

FIGURE 3 is an exploded perspective view of the components comprising the chuck, holder and blade assembly shown in FIGURE 2;

FIGURE 4 is a vertical sectional view of a fixture that can be employed according to the principles of this invention for centering an annular blade with respect to the clamping rings that comprise the holder for the blade, the blade and clamping rings being shown in their operative relation to the fixture for the practice of the centering procedure;

FIGURE 5 is a top perspective view of the fixture illustrated in FIGURE 4, shown in its condition for preliminarily centering the blade and clamping rings relative to one another;

FIGURE 7 is a top plan view of the fixture, in the condition illustrated in FIGURE 6;

FIGURE 8 is a top perspective view of the fixture shown in FIGURES 4-7, but in its condition for use in establishing the tension ring in its position at which it imposes the desired circumferential tension upon the blade; and

FIGURE 9 is a vertical sectional view of the fixture in the condition illustrated in FIGURE 8.

Referring now more particularly to the accompanying drawings, the numeral 5 designates generally the cutting head portion of a machine tool having a cup-shaped rotatable chuck 6 on which there is coaxially mounted a thin annular blade 7 having an inside diameter cutting edge. The chuck is carried on a coaxial rearwardly projecting spindle 8 mounted in a suitable bearing head 9 and rotatably driven, through a belt transmission 10, by an electric motor 11.

The annular blade 7 is concentrically mounted on the rim of the cup-shaped chuck by means of a blade holder 12 that comprises front and rear clamping rings 13 and 14 that engage around the outer marginal edge portion of the blade. The rear clamping ring 14 abuts a flat forwardly facing surface 16 on the rim of the chuck, and the

blade holder 12 is releasably secured to the chuck by cap screws 18 which extend through the two clamping rings and are threaded into the chuck. Locating pins 19 on the chuck (see FIGURE 3), projecting forwardly from its rim to be received in closely fitting holes in the rear clamping ring, serve to accurately establish the blade holder in concentric relation to the chuck.

The blade is maintained under circumferential tension by means of a tension ring 17 which is secured to and partly received in the front clamping ring 13, and which holds the central portion of the blade axially offset from its outer marginal edge portion.

As is conventional, the inner marginal edge portion of the annular blade 7 is coated with diamond bort, as at 20. Means (not shown) may be provided for delivering liquid cooling medium to the blade, and the cylindrical wall of the cup-shaped chuck may be provided with circumferentially spaced ports or outlets 21 through which such liquid can escape into a collector housing 22 that surrounds the chuck and blade assembly.

The cooperating clamping rings 13 and 14 that comprise the blade holder 12 have opposing flat axially inner faces 13' and 14' between which the blade is clampingly confined, and their axially outer faces are likewise flat and are parallel to their axially inner faces. The two clamping rings preferably have equal inside and outside diameters, but the rear clamping ring 14 has a somewhat greater axial thickness than the front clamping ring 13. One of the clamping rings (preferably the front ring 13) has locating pins 23 projecting therefrom and receivable in closely fitting holes in the other clamping ring, so that said two rings can be locked in accurately concentric relation to one another while their axially inner faces are lightly flatwise engaged with a blade between them. The clamping rings can be drawn together and secured in clamping relation to the blade by means of a plurality of cap screws 24 that extend through circumferentially equi-spaced holes 25 in the rear clamping ring and into coaxial threaded holes 26 in the front clamping ring.

It will be apparent that the several locating pins 19 and 23 serve to establish the clamping rings in accurate coaxial relationship to one another and to the chuck 6, and hence if a blade 7 is established in concentric relationship to the clamping rings 13 and 14 it will be concentric to the chuck. Centering the blade relative to the rings can be accomplished easily and accurately by means of the method of this invention, which is readily practiced with the aid of a fixture 28 illustrated in FIGURES 4-7.

Briefly, the method of this invention consists in clampingly confining the blade between a pair of clamping members having opposing flat clamping surfaces and which leave the central portion of the blade visible around substantially the entire inner edge thereof; disposing the clamping rings 13 and 14 in assembled relation to the blade but with their axially inner faces 13' and 14' in only light flatwise contact with opposite faces of the blade, the locating pins 23 being utilized to establish and maintain the clamping rings in concentric relationship to one another; then, by reference to the inner edge of the blade and a circumferential surface on one of the clamping rings, shifting the clamping rings in unison and edge-wise relative to the blade until the clamping rings are accurately concentric to the blade; and finally, while holding the clamping rings against displacement relative to the blade, tightening the cap screws 24 to draw the clamping rings axially toward one another and releasably lock them in clamping relationship to the blade.

The fixture 28 (see FIGURES 4 and 5) comprises a base 29 that has an annular upwardly facing flat surface 30 surrounding a raised central boss 31 with a flat upper surface 32. A central stud or post 33 having its upper end portion threaded as at 34 projects coaxially upwardly from the boss.

The height of the central boss 31 is equal to the axial

thickness of the front clamping ring 13, and the latter is adapted to rest on the annular surface 30 with its rear flat face 13' uppermost and flush with the upper surface 32 of the boss. The diameter of the boss is somewhat less than the inside diameter of the clamping rings to permit a certain amount of radial shifting of the front clamping ring on the base, and the ring is preliminarily centered by establishing a substantially uniform radial spacing between it and the boss.

With the front clamping ring in place on the fixture, a blade 7 is placed thereon, with its central portion flatwise overlying the upper surface 32 of the boss 31 and its peripheral portion overlying the clamping ring. To assist in preliminarily centering the blade, an annular centering guide 35 can be placed over the stud 33 before the blade is set in place. The centering guide has a close sliding fit on the stud and has an outside diameter slightly smaller than the inside diameter of the blade; hence by inspection the blade can be so placed on the fixture that there is substantially uniform radial spacing between the blade and the centering guide all around the latter. The centering guide can then be removed if desired, the stud guiding it in upward movement to prevent its engagement with the inner edge of the blade by which the blade might be damaged.

At this point the rear clamping ring 14 can be set in place over the peripheral portion of the blade, care being taken to engage the locating pins 23 in their proper holes so that the clamping rings are locked thereby in coaxial relationship to one another. Preferably the cap screws 24 are at this time loosely inserted in their holes in the clamping rings. It will be understood that the blade is provided with somewhat oversize holes through which the locating pins 23 and the cap screws 24 can readily pass.

Next an annular clamping element 36 having a flat bottom surface is placed over the blade. The clamping element 36 and the boss 31 provide the clamping members by which the blade is confined against edgewise motion while the clamping rings 13 and 14 are shifted into concentricity with the blade, according to the method of this invention. The clamping element 36 has an outside diameter equal to that of the boss 31 and has an inside diameter somewhat larger than that of the blade so that the inner marginal edge portion of the blade is visible all around the same. To facilitate setting the annular clamping element in place on the fixture and removing it therefrom, it can be provided with a pair of lifting knobs 37 which can comprise thumb screws threaded down into the top of the clamping element at diametrically opposite locations.

Downward clamping force is applied to the clamping element by means of a nut 38 which is threaded onto the upper end portion of the stud 33 and bears against the hub 39 of a yoke 40 having opposite arms extending radially from the hub to overlie the top of the clamping element. The stud 33 is closely received in the hub 39 of the yoke.

After the clamping element 36 and yoke 40 are installed on the fixture and the nut 38 is tightened, the clamping rings can be moved in directions edgewise of the blade, so that they can be brought into concentricity to it, while the locating pins 23 hold the clamping rings in concentric relation to one another.

To facilitate small movements of the clamping rings by which accurate centering is readily achieved, and to hold them against inadvertent shifting, the fixture is provided with a plurality of circumferentially spaced posts 42, in each of which there is threaded a thumb screw 43 that extends radially inwardly to have its inner end bear against the outer circumferential surface of the front clamping ring 13. As shown, there are four such thumb screws, located at 90° intervals around the fixture, so that the clamping rings can be slowly moved in any desired radial direction by turning the appropriate thumb-

screw inwardly while simultaneously turning outwardly the diametrically opposite thumbscrew.

Although centering of the clamping rings relative to the blade might be accomplished with the aid of an outside caliper or the like, it is preferred to use the optical instrumentation illustrated in FIGURES 4, 6 and 7, which eliminates the need for physical contact with the inner edge of the blade and which comprises a microscope or magnifying lens system 44 and an inverted U-shaped stand 45 upon which the microscope is mounted and which is in turn adapted to rest upon diametrically opposite portions of the top surface of the rear clamping ring 14. The legs of the microscope stand are high enough so that its bight portion clears the top of the stud.

At the bottom of one leg of the stand there is a foot 46 (best seen in FIGURES 6 and 7) which extends circumferentially to opposite sides of said leg and carries near each of its ends a roller 47 that is adapted to ride on the upper face of the rear clamping ring, radially outwardly of the cap screws 24. The other leg of the stand carries at its bottom a single roller 48 which likewise rides on the rear clamping ring and cooperates with the rollers 47 to provide a stable and rotatable tripod mounting for the stand. Guide pins 49 project downwardly from the foot 46, near the opposite ends thereof and substantially in line with the axes of the rollers 47, to engage the radially inner surface of the rear clamping ring for concentricity reference. A spring arm 50 (best seen in FIGURE 4) projects downwardly from the foot, circumferentially intermediate the guide pins, to engage the outer circumferential surface of the rear clamping ring and thus urge the guide pins 49 into firm engagement with its inner edge.

The lens system 44 is provided with a series of parallel calibration lines 51 (see FIGURE 7) which are adapted to be referenced to the inner edge of the blade, and the microscope is secured to the bight portion of the stand 45 by means of an adjustable clamping bracket 52 so that the microscope can be adjusted along the bight portion to bring its calibrations into initial register with the inner edge of the blade. Readings are taken with the microscope at locations at which the legs of the stand 45 are substantially in line with opposite thumb screws 43, as illustrated in FIGURE 7, and the clamping rings are shifted by means of said thumb screws until they are accurately centered with respect to the blade, as determined by reference to the microscope calibrations. Note that the yoke 40 of the clamping element is disposed out of alignment with the thumbscrews 43 so that it will not interfere with viewing the inner edge of the blade at the stations which the thumbscrews define.

Since the thumbscrews 43 hold the clamping rings against undesired radial shifting, the microscope stand can be removed from the fixture after the clamping rings are centered relative to the blade, to facilitate tightening of the cap screws 24.

When the cap screws are all tightened, to clampingly secure the blade against displacement relative to the blade holder 12, the nut 38, yoke 40 and clamping element 36 are removed from the fixture and the blade holder 12 is turned upside down on the fixture, to dispose the front clamping ring 13 uppermost, in preparation for use of the fixture to radially tension the blade in accordance with the method of this invention.

Referring to FIGURES 3 and 9, it will be noted that the tension ring 17 has a generally L-shaped cross-section, with a radially outwardly projecting circumferential flange 53 at its front that is adapted to overlie the flat front surface of the front clamping ring. The axially intermediate portion of the tension ring has an outside diameter such as to provide a close sliding fit in the front clamping ring, and its rear portion is beveled or tapered rearwardly so that at its axially inner end 54 its diameter is substantially smaller than the inside diameter of the clamping rings and it is substantially narrow radially.

The function of the tension ring, of course, is to hold the central portion of the blade in axially offset relation to its peripheral portion, to thereby maintain circumferential tension in the blade. Hence when the tension ring is installed in the blade holder 12 it projects rearwardly beyond the plane of the axially inner surface 13' of the front clamping ring, and the distance by which it projects beyond said plane determines the amount of circumferential tension that it applies to the blade. That distance, in turn, can be controlled by means of shims 55 (see FIGURE 3) that are interposed between the front surface of the front clamping ring 13 and the rear surface of the flange 53 on the tension ring.

In the assembled blade holder the tension ring is releasably secured to the front clamping ring by cap screws 56 that extend through circumferentially spaced holes in the flange 53 and into coaxial threaded holes in the front clamping ring, proper alignment of such holes in the respective rings being assured by rearwardly projecting locating pins 57 in said flange that are received in closely fitting holes in the front clamping ring.

If the blade is to be placed under circumferential tension that is uniform all around it, the tension ring must be moved into the front clamping ring with a purely translatory axial motion. Tightening of the cap screws 56 cannot be relied upon to achieve this. Instead, according to the present invention, the tension ring is loosely assembled into the front clamping ring and the cap screws 56 are loosely inserted into the holder, and then force is applied coaxially to the tension ring to urge the same into the front clamping ring until the tension ring reaches a position at which it effects the desired amount of axial offset of the central portion of the blade; and thereafter, while the tension ring is maintained in that position by the continued application of coaxial force thereto, the cap screws are tightened to lock the tension ring in that position.

The apparatus by which such purely translatory axial motion of the tension ring is effected comprises a force applying plate 59 (see FIGURES 8 and 9) having a central hole in which the stud 33 on the fixture is receivable with a close sliding fit and having a diameter to overlie the front surface of the tension ring all around the same while leaving the cap screws 56 exposed for ready access. The nut 38, cooperates with the plate 59 to apply force to the tension ring uniformly and simultaneously at all points around it. The nut is turned down on the stud to bear upon the plate 59 and thus drive the tension ring straight down until its flange 53 engages the front face of the front clamping ring 13 or a shim or shims 55 overlying the same. At that point the tension ring is in the position to cause the desired tensioning of the blade, and the cap screws 56 are tightened to lock the tension ring in that position. Thereafter the nut 38 can be backed off of the stud and the assembled blade holder can be removed from the fixture for mounting on the chuck.

The reason the blade holder 12 is turned upside down on the fixture between the blade centering and blade tensioning steps is to provide spacing, during the latter step, between the blade and the flat upper surface 32 of the central boss 31 on the fixture, so that the central portion of the blade can be displaced downwardly without interference from the boss. Such spacing of course results from the fact that the rear clamping ring has a substantially greater axial thickness than the front one.

Preferably the blade holder, with the tension ring properly attached thereto, is assembled to the chuck and accurately balanced before a blade is installed therein and as a final step in manufacture of the apparatus. Provision is made (either by unique locations of the several locating pins 19, 23 and 57 or by means of marks etched on the several parts) for assuring that the parts of this balanced assembly will always be reassembled in the angular relationship to one another that they had during the balancing operation. It will be apparent that two

balanced blade holder assemblies are desirably provided for a chuck so that a blade can be installed in one holder while the other is in use.

If desired, the base portion of the fixture 28 can be 5 rotatably mounted on a sub-base 60, so as to facilitate the blade centering operation. The sub-base is preferably provided with a locking screw 61 that is engageable with the base to lock it against rotation relative to the sub-base, such locking being desirable when the fixture is in use for installation of the tension ring.

From the foregoing description taken together with the accompanying drawings it will be apparent that this invention provides a simple method and means for accurately centering an annular blade having an inside diameter cutting edge in a holder by which the blade can be mounted on a rotatable chuck, and for circumferentially stressing the blade uniformly all around its inside diameter.

What is claimed as my invention is:

1. The method of installing a thin annular blade having an inside diameter cutting edge in a holder by which the blade can be concentrically secured to a rotatable chuck, and which holder comprises a pair of clamping rings having opposable axially inner faces adapted to 15 clampingly engage the outer marginal edge portion of a blade, said method comprising the steps of:

(A) locking the clamping rings into concentric relation to one another with their said inner faces lightly engaging opposite surfaces of a blade so that the rings are shiftable in unison edgewise relative to the blade;

(B) by clampingly engaging the opposite surfaces of the blade at circumferentially spaced areas in an annular zone radially intermediate the inner edge of the blade and the inner circumferences of the clamping rings, confining the blade against edgewise displacement;

(C) while the blade is thus confined, and by reference to the inside edge of the blade and a circumferential surface of one of the clamping rings, shifting the clamping rings edgewise relative to the blade to bring them into a position of concentricity with the blade;

(D) while confining the clamping rings against displacement out of said position, drawing them together and locking them in clamping relationship to the blade; and

(E) releasing the clamping engagement of the blade in said annular zone thereof.

2. The method of claim 1, further characterized by the steps of circumferentially tensioning the blade uniformly all around the inside circumference thereof after the clamping rings are established in clamping relationship to the blade, by the use of a tension ring which is 40 receivable in one of the clamping rings and which engages a radially narrow annular zone of the blade spaced inwardly of the radially inner surfaces of the clamping rings, said steps comprising:

(A) restraining the clamping rings against axial movement;

(B) applying axial force to the tension ring uniformly and simultaneously at all points around the same to translate the tension ring axially inwardly relative to said one clamping ring until the tension ring reaches a position at which it holds the central portion of the blade axially offset from the remainder of the blade by a predetermined distance;

(C) while maintaining axial force on the tension ring to hold it in said predetermined position, locking the tension ring to said one clamping ring; and

(D) thereafter releasing said axial force on the tension ring, the tension ring retaining its said position by reason of its being locked to said one clamping ring.

3. The method of establishing a predetermined circum-

ferential tension all around an annular cutting blade which has an inside diameter cutting edge and which has its outer marginal edge portion clamped between a pair of clamping rings that provide a holder, by the use of a tension ring which is receivable in one of the clamping rings and engages a narrow annular zone of the blade spaced radially inwardly from the radially inner surfaces of the clamping rings, which method comprises the steps of:

- (A) confining the clamping rings against axial displacement;
- (B) applying axial force to an axially outer surface of the tension ring uniformly and simultaneously at all points around the same to move the tension ring into said one clamping ring with a true translatory axial motion until the tension ring reaches a position at which it holds the central portion of the blade axially offset from the remainder of the blade by a predetermined amount; and
- (C) while maintaining said axial force at the value to hold the tension ring in said position, locking the tension ring to said one clamping ring.

4. The method of installing a thin annular blade having an inside diameter cutting edge in a holder by which the blade can be concentrically secured to a rotatable chuck and by which the radially inner portion of the blade is maintained under circumferential tension, and which holder comprises a pair of clamping rings having opposable flat inner surfaces adapted to clampingly engage opposite faces of the blade at its outer marginal edge portion and a tension ring securable to one of the clamping rings and which has an annular inwardly facing surface that engages the blade around a radially narrow zone thereof to hold the central portion of the blade axially offset from the outer marginal edge portion thereof and thus maintain the blade under circumferential tension, said method comprising the steps of:

- (A) locking the clamping rings in concentric relationship to one another and with their said inner faces lightly flatwise engaging opposite surfaces of a blade around its outer marginal edge portion so that the clamping rings are shiftable in unison relative to the blade in directions edgewise thereof;
- (B) clampingly confining the blade against edgewise motion by flatwise engaging the opposite faces thereof in a zone within the embrace of the clamping rings and spaced from the inner marginal edge portion of the blade so that the inner marginal edge portion of the blade is readily visible;
- (C) by reference to the inner edge of the blade and a circumferential surface of one of the clamping rings, and while the blade is clampingly confined against edgewise motion, shifting the rings as necessary to bring them into concentricity with the blade;
- (D) drawing and holding the clamping rings together in clamping relationship to the blade to fix them in concentric relationship to it;
- (E) confining the clamping rings against axial motion;
- (F) inserting the tension ring into one of the clamping rings with an axial translatory motion by applying axial force uniformly and simultaneously at all points around the tension ring, until it reaches a position at which it effects a predetermined axial offset of the central portion of the blade; and
- (G) while maintaining axial force on the tension ring to hold it in said position, locking the tension ring to one of the clamping rings.

5. The method of installing a thin annular cutting blade having an inner edge and an outer edge in a holder by which the blade can be concentrically secured to a rotatable chuck with assurance that the inner edge of the blade which constitutes its cutting edge will be accurately concentric with the axis of rotation of the chuck, and which holder comprises

a pair of clamping rings having opposable axially inner

faces adapted to clampingly engage the outer marginal edge portion of the blade, said method comprising the steps of:

- (A) locking the clamping rings into concentric relation to one another with their said inner faces lightly engaging the opposite sides of the blade, so that relative edgewise shifting can be effected between the blade and the rings;
- (B) holding the blade flat by clamping the portion thereof intermediate its inner edge and the inner circumferences of the clamping rings between two flat rigid surfaces;
- (C) while the blade is thus held flat and by reference to the inner edge of the blade and a circumferential surface of one of the clamping rings, effecting relative edgewise shifting between the blade and the rings as needed to bring the rings and the inner cutting edge of the blade into concentricity;
- (D) while confining the blade and the clamping rings against relative displacement out of concentricity, drawing the clamping rings together and locking them in clamping relationship to the blade; and
- (E) releasing the blade from the two flat rigid surfaces between which it was held flat.

6. The method of claim 5, further characterized by the steps of circumferentially tensioning the blade uniformly all around the inside circumference thereof after the clamping rings are established in clamping relationship to the blade, by the use of a tension ring which is receivable in one of the clamping rings and which engages a radially narrow annular zone of the blade spaced inwardly of the radially inner surfaces of the clamping rings, said steps comprising:

- (A) restraining the clamping rings against axial movement;
- (B) applying axial force to the tension ring uniformly and simultaneously at all points around the same to translate the tension ring axially inwardly relative to said one clamping ring until the tension ring reaches a position at which it holds the central portion of the blade axially offset from the remainder of the blade by a predetermined distance;
- (C) while maintaining axial force on the tension ring to hold it in said predetermined position, locking the tension ring to said one clamping ring; and
- (D) thereafter releasing said axial force on the tension ring, the tension ring retaining its said position by reason of its being locked to said one clamping ring.

7. Apparatus for installing a thin annular cutting blade having an inner cutting edge and an outer edge, in a holder by which the blade can be concentrically secured to a rotatable chuck, with assurance that the inner cutting edge of the blade will be accurately concentric with the axis of rotation of the chuck, and which holder comprises a pair of clamping rings having opposable axially inner flat faces adapted to clampingly engage the outer marginal edge portion of the blade, cooperating locating means on the clamping rings for non-clampingly locking them in concentric relation to one another so that they may be shifted in unison edgewise relative to a blade loosely received between their inner faces, and cooperating force applying means on the clamping rings for establishing them in clamping relationship to a blade therebetween, said apparatus comprising:

- (A) a base having
  - (1) an annular upwardly facing surface on which one of the clamping rings may be set with its flat inner face uppermost, and
  - (2) a central boss, the top of which provides an elevated planar surface which is uniformly spaced above said annular surface by a distance equal to the thickness of said one ring,

11

- so that when said one ring is set on said annular surface with its said flat inner face uppermost, that face lies in the plane of said planar top surface of the boss;
- (B) an upright stud on the base coaxial with the central boss and projecting upwardly from the top of the boss;
- (C) an annular clamping member encircling the stud and cooperable with said elevated planar top surface of the boss to clampingly confine a blade placed on the boss against edgewise displacement, said clamping member being of a size to engage the blade at an area thereof that is radially spaced from its inner and outer edges, so that the clamping member does not interfere with placement of the other clamping ring on the outer marginal edge portion of the blade and so that the clamping member leaves visible substantially all the inner marginal edge portion of the blade;
- (D) means cooperable with the clamping member and the stud for applying downward clamping force to the clamping member to thereby securely clamp the blade to the base; and
- (E) circumferentially spaced means fixed with respect to the base and engageable with one of the clamping rings for adjustably shifting the clamping rings in unison and edgewise of the blade in directions radial to the blade as needed to bring the rings into concentricity with the blade as determined by the spacial relationship between the inner edge of the base and a circumferential surface on one of the clamping rings.
8. The apparatus of claim 7, further characterized by means to facilitate ascertaining the spacial relationship between the inner cutting edge of the blade and said circumferential surface on one of the clamping rings, comprising

12

a frame member having spaced legs adapted to set on the upper surface of the uppermost clamping ring and thereby support the frame for stable rotation about the common axis of the connected clamping rings, means on the frame guidingly engageable with a circumferential surface portion of one of the connected clamping rings to constrain the frame to rotation about the common axis of the clamping rings, and optical means on the frame through which the inner edge of the blade can be observed, and having calibrations referable to the inner edge of the blade to facilitate observation of departures of the blade from concentricity with said circumferential surface on said one of the connected clamping rings as the frame is rotated.

UNITED STATES PATENT OFFICE
CERTIFICATE OF CORRECTION

Patent No. 3,324,539 Dated June 13, 1967

Inventor(s) C.E. Cleland

It is certified that error appears in the above-identified patent and that said Letters Patent are hereby corrected as shown below:

Column 11, line 31 (Claim 7, element E, line 7 thereof): "base" should read -- blade --.
